UNITED STATES PATENT OFFICE.

JOHN H. YOUNG, OF RANDOLPH, NEW YORK, ASSIGNOR TO BORDEN'S CONDENSED MILK COMPANY, OF NEW YORK, N. Y., A CORPORATION OF NEW JERSEY.

SHEET FEEDING AND CUTTING MACHINE.

1,171,011.

Specification of Letters Patent Patented Feb. 8, 1916.

Application filed December 10, 1913. Serial No. 805,711.

To all whom it may concern:

Be it known that I, JOHN H. YOUNG, a citizen of the United States, residing at Randolph, in the county of Cattaraugus and State of New York, have invented a new and useful Sheet Feeding and Cutting Machine, of which the following is a specification.

My invention relates to improvements in machines employed to feed and cut sheets of material as, for example, tinned sheet-metal into equal subdivisions, of rectangular contour, adapted to serve for blanks in manufacture of well-known containers or cans employed, for instance, in storage and transportation of condensed milk, and the objects of my invention comprise provision of means whereby said feeding, and cutting, of required blanks may be accomplished automatically, more exactly, rapidly, and economically, than heretofore, and with less dependence on manual labor and skill. I attain these objects by aid of my improved mechanisms, or their equivalents, and their combinations with each other and with old instrumentalities as hereinafter described, and as illustrated, for example, in the accompanying drawings, in which—

Figure 1 is a plan view of an organized machine containing my said improvements and combinations; Fig. 2 is, on enlarged scale, a sectional view on line 2—2 of Fig. 1 seen in the direction of the arrow, and showing elements of my primary feeding device and therewith associated parts, some of them in side elevation; Fig. 3 is, on same scale as Fig. 2, a side elevation of parts shown in the latter, and also a diagram of the primary cutters; Fig. 4 is, on a somewhat still larger scale, a sectional view on the line 4—4 of Fig. 1, certain parts being shown in elevation; Fig. 5 is, on still larger scale, a horizontal sectional view, on line 5—5 of Fig. 4, of details of a member of my sheet-lifting devices; Fig. 6 is, on an enlarged scale, a side elevation of my secondary feeding device, including a diagram of the secondary cutters, certain shafts being shown in vertical section; Fig. 7 is, on same scale as Fig. 6, a longitudinal sectional view on the line 7—7 of Fig. 1; Fig. 8 is a cross-sectional view on the line 8—8 of Fig. 7; Fig. 9 is a longitudinal sectional view, on the line 9—9 of Fig. 1, showing some details at the receiving end of my secondary feed-

ing device; Fig. 10 shows, on enlarged scale, a detail view of certain gate and guard devices of the guide rails of my primary feeding devices; Fig. 11 is a cross sectional view of Fig. 10 taken on the line 11—11 of the latter; Fig. 12 shows, on enlarged scale, certain details of one of the pivoted rests of the sheet carriage; Fig. 13 is, on enlarged scale, a front view, partly sectional, on the line 13—13 of Fig. 14, of details of the clutch which controls the operation of said feeding devices; Fig. 14 is a vertical sectional view of Fig. 13 on the line 14—14 of the latter.

Rotary, and other, cutters designed to cut sheets of various materials, including metal, are well-known and constitute by themselves no part of my present invention but the feeding and subdivision of the initial sheets thereby cut into pluralities of smaller sheets, or blanks, of required proportions and rectangularity, has hitherto required more manual skill, precision, care, and time on the part of the operators than is industrially economical. The manual separation of each initial sheet from the pile of similar sheets in which it is received by the operators, its subsequent guidance to correct presentation to the cutters, the subsequent handling of the resulting divisions in order to insure their being in turn fed and guided in correct presentations to the same, or other, cutters to effect their subdivision, into blanks of required proportions and rectangularity, with least possible waste of time and material, have hitherto required high degrees of tactile skill and intelligent watchfulness with which my invention dispenses. In other words, my machine takes each initial sheet separately from the pile, cuts it into the required subdivisions, and delivers the final product, or blanks, of required proportions and rectangularity, with unprecedented speed and without the materials being, at any time, guided, or otherwise touched, by the operators. These results I believe to be attributable to my novel devices and their combinations with each other and with old devices as hereinafter described, it being understood that I do not confine myself to exactly the forms and arrangements illustrated in the drawings, equivalents of which are to be also regarded as within the purview of my invention.

Referring now to the drawings, my illus-

trative machine comprises, viewed in its broadest aspect, the combination of two co-operating mechanisms, A and B, one of which, A, comprises what I term my primary feeding devices and therewith associated cutting element, C, and the other, B, what I term my secondary feeding devices and the therewith associated cutting elements, D. The element, C, comprises a group of three ordinary rotatory cutters, 1, 1^a, 1^b (Figs. 1 and 3) cooperating, as usual, to trim to exact location and parallelism with each other the outside edges of each initial sheet, e, (Figs. 1 and 4) and, simultaneously, to sever the remainder into equal halves. The element, D, comprises a group of similar cutters, five in number, 1^c, 1^d, 1^e, 1^f, 1^g (Figs. 4 and 6) operating similarly to trim and to subdivide each of said halves into four equal rectangular blanks, d, d', shown by dotted lines as deposited in the diagrammatically indicated receiving box, 2 (Fig. 6). The cutters and blanks, as the function, are merely diagrammatically shown, likewise the usual therewith co-acting feed rollers, 3, 4, and delivery rollers, 5, 6, usually associated with such cutters. In my primary feeding device, A, includes a suitable frame comprising longitudinal members or rails, 7 and 8, and transverse disposed ends of 7 and 8 being supported upon the usual frame, 9, of the cutters, C (see Figs. 1, 2, 3) and their outer ends by posts, 10, bearing on the floor (Figs. 2 and 3). 7 and 8 support standards, 11 and 12, carrying blocks, 13, 14, within which a shaft, 15, is rotatably mounted. The shaft, 15, carries a face-cam, 16, and a box cam, 17, and is rotated by aid of a sprocket gear, 18, and chain, 19, actuated by means heretofore referred to. By pneumatic means, comprehensively designated as 20 (Fig. 4) to lift and drop a sheet, are actuated by aid of the beam, 16, and comprise a link, 21, containing, adjacent its upper end, a slot, 22 (Fig. 2) through which loosely passes the shaft, 15. The link, 21, carries, near its lower end, arms, 22, 22, which support rails, 23, 23, to which are secured pneumatic suckers, 24, 24. These suckers it will be noted on reference to the drawings (see Fig. 1) are four in number and each so disposed as to contact, when required, with the sheet adjacent to one of its four corners. This plurality and disposition of the suckers is important in that I have discovered I am thereby enabled to overcome the well-known tendency of the top sheet of the pile to adhere thereto, the simultaneous application of four widely separated lifting means at near the four corners of the sheet enabling the latter to be lifted with certainty and comparatively little difficulty or disturbance of the remaining elements of the pile. The upper end of the link, 21, carries a roller, 25, disposed to bear on, and be lifted by, the cam, 16, whereby the suckers are intermittently lifted together with a sheet thereto pneumatically adhering by means hereinafter described. The sheet thus lifted from the pile is, as will be shown hereafter, dropped and supported horizontally in advance of the feed-rollers, 3 and 4, of the cutters, C, of My primary feeding device comprises percussive means to, at this stage, project the sheet horizontally between said feed rollers, to wit, what I term a "kicker," or "driver," 26, slidably mounted on a bar, 27, stationary supported by brackets, 28, carried by said frame. To intermittently impel the kicker along the bar, 27, in the direction of the feed rollers, I provide an arm, 29, carried by a shaft, 29, rotatably carried by the standards, 11 and 12, (Figs. 2 and 3). The arm, 29, is vibratory secured to the kicker, 26, by a pin and slot, connection, 26a, 28a, (Fig. 2). The shaft, 29, also carries a crank arm, 31, vibratory secured to a link, 31, by a pin and slot connection, 31a, 30a; the link, 31, contains, adjacent its free end, a slot, 31b, (Fig. 2) through which loosely passes the shaft, 15. A suitable projection, preferably the usual roller, not shown, is carried by the link, 31, so disposed as to ride in the cam groove, 17, of the box cam, 17. The construction is such that rotation of said cam intermittently causes the kicker to slide briskly along the bar, 27, and impart a percussive and forwardly extended drive to the sheet supported as hereinafter described whereby the latter is driven off of its supports substantially horizontally toward the cutters, C. Conveniently feed and supports the sheets in quantity, or piles, in proper relation to my sheet-lifting device, 20, I provide platform cars, 34 and 35, adjacent the receiving end of my primary feeding device are located, as shown, frame elements, 36, 37 and 38, (Fig. 2) which support rails, 39, extending transversely of the direction of feed of said device. The wheels, 40, of the cars or truck with said rails. On the platforms, 34 and 35, of said cars are manually loaded in piles, 42, the alike individual sheets, e, this being done when a car is, for example, in the position of 34 in Fig. 1, after which so loaded it is rolled to beneath the suckers, 24, in the position of 35 in Fig. 1, where it remains until the latter have successively lifted each sheet from the pile. Meanwhile, the other car is being similarly loaded to be, in turn, rolled into said last mentioned position after the emptied car is withdrawn and so on indefinitely, thus insuring desired continuity of supply to the suckers. 180

My means for producing the required exhaustion of air in the suckers, 24, comprise the following, viz.—A pump comprising a cylinder, 43, and piston, 44, is stationarily supported, adjacent one end of the shaft, 15, (Figs. 1 and 4). The piston, 44, is reciprocated by means of a crank-arm, 45, carried by said shaft and coupled with said piston by the link, 46. Suitable atmospheric connection between the interiors of the cylinder, 43, and of the cups of the suckers, 24, is secured by means of a flexible tubing, 47, extending from said cylinder to rigid tubing, 47^a, carried by the link, 21, and two flexible tubings, 48, each extending from said piping to connect with a rigid duct, 49, carried by each rail, 23, respectively, each of which ducts makes connection with two of the suckers through the hollow stem, 50, thereof, which passes through and is supported by a bracket, 51, carried by one of the rails, 23, (Fig. 5). The cylinder, 43, is provided with an aperture, 52, (Fig. 4), located immediately below the bottom of the piston, 44, at the end of the latter's up stroke, whereby air is admitted to break the exhaust in the suckers. To prevent cushioning on the down stroke, the cylinder is provided with openings, 54, closed by a relief valve member, 55, slidably mounted on a headed pin, 43^a, carried by the cylinder, and normally held against the wall thereof, to close said openings, by a spiral spring 56 encircling said pin and bearing against the head thereof and against said valve.

Guide-rails, 57, (Figs. 2 and 4), supported by aid of the frame of the primary feeding device, are disposed on each side of the path of the sheets toward the feed rolls, 3, 4, and are spaced-apart sufficiently to permit of the sheets being freely driven by the kicker as aforesaid while preventing undue lateral divergence or side-play. Between the guide-rails, 57, are table-bars, 58, supported by said frame and extending from slightly behind my lifting and dropping device, 20, to near the feed rollers 3, 4, of my primary feeding device. On these table-bars the sheets, as their momentum imparted by the kicker wanes, finally fall and glide forward to said rollers. To further insure proper delivery of the sheets to the feed rollers, I provide spring fingers, 59, 60, (Fig. 2), depending from suitable stationary supports, as shown, and having their free ends disposed to contact yieldingly the upper surfaces of the driven sheets, thus preventing the latter from unduly jumping upward.

To guide each sheet laterally during its upward lift from the pile and to loosely support it, after being dropped, in horizontal presentation to and exactly in the path of the kicker, I provide yielding, oscillatable guide-rests, or T's 61, pivotally supported on brackets, 62, carried by the plat-

form of each car, 34, 35. The conformation, location and disposition of said rests relatively to the platform, the pile, 42, of sheets, and the lifting device, are such that, (as shown in Figs. 1, 2, and, more particularly, 70 in Fig. 12) they are, when at rest, in normal position, inclined inwardly at an angle sufficient to project into the path, and to insure yielding contact thereby of the edge, of the sheet, during its uplift, whereby they 75 laterally guide it, as indicated by dotted lines, 63, in Fig. 12, and, after it has cleared them, are returned, usually by gravity, to their original position wherein their tops are normally held, by aid of gravity, projecting 80 into, and in a plane transverse of, the pathway of the sheets, and in which position the rests then underlie the suspended sheet. When the sheet is afterward dropped, in the same vertical path through which it was 85 lifted, by the breaking of the exhaust, it falls upon them, at which stage they act as rests or T's disposed to support the thereon deposited sheet against displacement by gravity and with its edge disposed directly 90 in the path of the advancing kicker 26. It will be noted that as shown, particularly by Fig. 2, the tops of the rests 61 are, when supporting a sheet, on a level above that of the trucks or table 58. It will also be noted 95 that, as shown particularly by Figs. 1 and 4, the rests 61 are spaced-apart thus leaving between them, below their tops, an inter-space or pathway in which the kicker 26 is, to an extent, reciprocatable. It will also be 100 noted that, as shown particularly in Fig. 2, the kicker or driver 26 is normally out of contact with the sheet supported on the T's, is in alignment with an edge of the sheet and with the said pathway, and that the construction is such that the kicker is slidably supported at all times out of contact with the rests or T's 61 and their supporting means which, in this instance, include the brackets 62, the car platform, etc. These 105 features of my construction are of importance in that they tend to insure the required delivery by the kicker, or driver, of an entirely unimpeded, sweeping, percussive stroke squarely and certainly against the 110 very edge of the sheet, and carried through beyond its location prior to being struck. It is obvious that a stroke of such character could not with any certainty be delivered if the sheet were supported upon a therewith 115 coextensive, or larger, surface or table with which the kicker must, or could, contact. In other words, in order to effectively drive the sheet off of the rests or T's to destination, I have discovered that the kicker 120 proper should encounter the least possible contact, friction or resistance other than that of the edge of the sheet during its forward impulsion or swing, and I consequently provide means whereby it is slidably supported 125 130

independently of all other parts or constituents of the machine, in which directly it supports the sheets. Moreover, by my construction as described and shown, the driver during its swift impulsion toward and in beyond the location occupied by the edge of the sheet thus follows it between the rails and in contact therewith until the momentum thus imparted to the sheet causes the latter to fly off of the face of the driver toward its destination, or predetermined location. The resulting capacity of my driver, or kicker, to thus unimpededly follow through, in the pathway between the spaced apart sheet rests, or T's, and at a perfectly uniform, or even increasing speed, as determined by the contour of the cam groove 32, an important factor in imparting the required range and stability to the flight of the sheet. Gateways 34, in the rails 32, (Figs. 2, 10 and 11), admit passage of the guide rests while the cars 33, 35, are being stopped to position beneath the lifting device. The gateways are provided with movable gates 36, pivotally supported on the guide rails 37, as shown in Figs. 10 and 11. These gates are closed after the car has been brought to operating position beneath the lifting device and, at this stage, constitute guards from which the guide rests 33, rebound toward normal position whenever struck outward by a quickly lifting sheet too far to recover such position by gravity. When this car has been unloaded the gates 36 are reopened to admit its withdrawal.

The operation of my primary feeding and cutting device thus results in pneumatically lifting the sheet at a rate of 15 ft. to 16 ft. per minute in horizontal presentation through a vertical path, each sheet separately from the pile, in guiding it to correct position during such lift, in dropping it in the said vertical path, to a position where it is horizontally movably supported on the T's 33, 35, striking one edge thereof so as to be guided and properly while guided, toward the primary cutters 17, 18 and by the latter to trim and subdivide it into halves, all of which operations are performed automatically, the movement of the sheet toward the cutters being horizontal, and in one direction, and likewise the movement of the resulting halves as they pass through the delivery rollers 5, 6, of the primary cutting element, C, which advances the halves or subdivisions of the sheet in the same plane simultaneously side by side to my secondary feeding devices. Intermediate lateral guards, 57, 57' (Fig. 1), are supported each side of the pathway of the halves to assist in maintaining their proper alignment. The operation having progressed to this point of dividing the initial sheet into halves, I next provide means coacting with those described, to the end that the said halves may, without pause, or manual manipulation,

be further simultaneously fed to, and each cut into quarters, by my secondary cutting element, D. These last mentioned means comprise what I term my "secondary feeding devices" 70 which, in their automatic attainment of the final product, are enabled to cooperate with the primary feeding and cutting devices, by aid of what I believe to be my novel diversion of the direction of secondary feed angularly to that of the primary feed. These secondary feeding devices, B, comprise horizontally disposed side-frame members, 67, and 68, extending, on a somewhat lower plane, at right angles to the analogous side members, 7, 8, of the primary feeding device. They are united by cross tie-bars, 69, 70 and 71, (Figs. 7 and 7) of which, 70 and 71, support stationary table bars or plates, 72 and 73, and also a stationary, centrally disposed, bar, 74, carrying a sequence of stationary, alike, stops, or teeth, 75, spaced apart not less than the width of the sheet, having their backs, as by notches 76, shaped and disposed 90 to positively engage and thus hold against backward movement, and their fronts, as by inclined surfaces 77, to slidingly contact with, and thus facilitate the advance thereafter of the aforesaid halves or subdivisions 95 of the initial sheet. Overhead guards, 74, 74', are supported above the thus constituted pathway of the sheets (Figs. 7, 8, 9) to prevent them from rising unduly upward. Supported on the bar, 74, opposite to, and 100 at a somewhat lower level than, the pathway of the sheets, as they advance from the primary feeding device, is a stationary, horizontal plate, or table, 76, (Figs. 7 and 8). Between the table bars, 72, 73, and their respectively adjacent frame members, 67 and 68, are therewith parallel subdisposed relatively to the pathway for the subdivisions of the initial sheet, movably supported, reciprocating, feeder bars, 77, and 77', each 110 carrying a sequence of thereby reciprocated teeth or stops, 78, of shape similar to those on the bar, 74. These feeder bars are connected at one end by a rod, 79, (Figs. 7 and 8) carrying rollers, 80, operating in 115 guideways, 81, formed by yokes, 82, depending from the frame members, 67, and 68, and at the other end, by a yoke, 83, which slidingly straddles the tie-bar, 69, (Figs. 7 and 9). The bars, 77, and 77', are reciprocated by aid of a therewith pivotally connected crank arm, 84, and link, 85, (Fig. 9) carried by a rotary shaft, 86, (Figs. 1, 3, and 6) provided with a spiral gear, 87, meshing with a spiral pinion, 88, carried 125 by a shaft, 89, journaled in the frame, 9, of the cutters C. The shaft, 89, is rotatable when desired by aid of a thereby normally loosely carried pulley, 90, rotated constantly by usual belting (not shown). To 130

rotatively connect, or clutch, the pulley with the shaft to operate my machine, I provide novel means as follows, viz.:—A split, expansible, ring, 91, (Figs. 13 and 14) carried within, and concentric with, the pulley, is proportioned and disposed to bear, when expanded, against the interior surface of the rim thereof. A carrier, 92, keyed to the shaft, 89, rotates therewith, and therein oscillatably supports a spindle, 93, having one end thereof flattened as at, 94, and located in the split, 95, of the ring, 91, (Fig. 13). The opposite end of the spindle carries an arm, 96, disposed so as to be acted upon by a cam block, 97, slidably mounted on the shaft, 89, and operated by a shift lever, 98, (Fig. 1). It follows that whenever the lever is pulled outwardly the ring, 91, is expanded so as to frictionally engage the pulley, 90, the shaft, 89, is thereby rotated, and the feeder bars, 76 and 77, reciprocated, the shaft, 15, being also simultaneously rotated by means of a sprocket pinion, 99, carried by the shaft, 89, (Fig. 1), which engages the aforesaid chain, 19, and thus the sprocket gear, 18, on said shaft, 15.

Another important co-operating element of my secondary feeding device is the divider, 100, (Figs. 1, 6—9) consisting of a stationary bar, 100, of angular cross-section, having its longitudinal angular apex upwardly presented in alignment with the direction of the cut made by the central cutter 1^a. The divider is supported by the side frame members, 67 and 68, and serves to deflect and separate the halves of the sheet, as they are advancing, from the delivery rollers, 5 and 6, of the primary cutting devices, to drop upon the receiving table, 76, whereby proper disposition of each half between the appropriate teeth, 78, of the reciprocating feed bars, 77 and 77^a, is insured, the positions of said valves, at the moment of initial action thereon by the divider, being cross-sectionally indicated by the dotted lines, 101, and 101^a, in Fig. 7. A stop 102, (Figs. 6 and 9) suitably supported by the frame, is proportioned and disposed to arrest undue forward movement of the halves, transversely of the path of the secondary feeding device, after their delivery to the latter.

The table, 76, is provided with a guard-rail, 103, to arrest backward movement of the thereto adjacent half of the initial sheet while the teeth, 78, are retrograding.

The operation of my machine is as follows:—One of the platform cars, as say 35, having been, while on one side of the primary feeding device, manually loaded with a pile, 42, of the initial sheets, *c*, is pushed by the operator into the position shown in Fig. 1 directly beneath the lifting device 20. The shift lever, 98, is then swung, to actu-

ate the clutch to turn on the power, as hereinbefore described. This causes the pneumatic suckers to descend to contact with the top sheet of the pile and adhering thereto lift it through a vertical path, while, to an extent, guided, toward required position, by lateral contact of the guide-rests 61, which, though yielding, tend to shift an eccentric position of the sheet without breaking the exhaust. The guide rests return to their normal position as soon as the sheet has ascended above them. It is then dropped in the said vertical path, by the breaking of the exhaust, into correct, and substantially horizontal, position at rest upon the tops of the guide rests, or T's and exactly in the path of the driver 26, which, being then sharply advanced, imparts a following-up stroke to the thereto adjacent edge of the sheet impelling the latter, substantially horizontally, over the table bars, 58, into the grasp of the feed rollers, 3, 4, of the primary cutting device, C, where it is trimmed, and divided into halves, by the group of primary cutters. The resulting subdivisions or halves are then advanced by the delivery rollers, 5, 6, of that device to a position where they are more widely separated by the divider bar, 100, and fall upon the table, 76, of the secondary feeding device. The mechanisms are so timed that as the halves drop into position, on the table, the reciprocating feeder bars, 77, 77^a, are at rest, or retrograding, hence each half is finally deposited between adjacent teeth of said bars and by their next forward movement advanced, at right angles to their former path, clear of the table and onto the table bars, 72, 73 and 74, the stationary stops, 75, of the latter arresting backward motion of the halves during the return stroke of the bars 72 and 73. Successive forward strokes of the bars thereafter operate to horizontally, simultaneously, feed the subdivisions or halves in procession sequentially, step by step, in a direction angular to that of my primary feed, toward the secondary cutting device, D, whereby each half is further trimmed and cut by the group of secondary cutters into four separate equal rectangular blanks, *d*, *d*¹, *d*², *d*³, which are finally projected by the delivery rollers, 5, 6, of that device into the receptacle E.

The shape and proportions of the operative edge of the cam, 16, are, as shown in Fig. 2, such as to insure the descent of the lifting device, 20, to contact, in turn, with each sheet of the pile from the highest to the lowest, and, also, after such contact, full gravity pressure, on each sheet, of the entire weight of said lifting device whereby pneumatic adhesion of the sheet to the suckers is promoted, the roller, 25, admitting clear passage thereunder of the least radius, as at 105, of the cam until the pile is 130

5 yond said cutter; means to further separate said subdivisions so advanced; means to receive and movably horizontally support, side-by-side, said subdivisions so separated; another stationarily supported cutter; means to engage, simultaneously, edges of each of said subdivisions; and means to reciprocate said last mentioned means in directions rectangular to said first mentioned direction, whereby said subdivisions are fed sequentially, in procession, and out of contact with each other toward said last mentioned cutter.

8. In a sheet-feeding, and cutting machine, the combination of a stationarily supported cutter; means to lift a sheet vertically between and above, drop it, in the same vertical path, on, a plurality of movable supports the tops of which are in alinement with said cutter; percussive means to project said sheet horizontally, off of said tops, in the direction of said cutter; means to advance its subdivisions of said sheet, simultaneously, side-by-side, in said direction beyond said cutter; means to receive and movably support, side-by-side, said subdivisions; means to engage, simultaneously, edges of each of said subdivisions; another stationarily supported cutter; and means to reciprocate said last mentioned means in directions rectangular to said first mentioned direction, whereby said subdivisions are fed sequentially, in procession, and out of contact with each other, toward said last mentioned cutter.

9. In a sheet-feeding and cutting machine, the combination of a cutter disposed to sever an initial sheet into smaller sheets; means to feed a sheet in one direction to said so severed, cutter; means to thereafter advance said smaller sheets, simultaneously in the same plane, side-by-side, in said direction, beyond said cutter; a plurality of cutters disposed to sever each of said smaller sheets into still smaller sheets; means to horizontally feed said smaller sheets sequentially, in procession out of contact with each other, in a direction at right angles to said first mentioned direction, toward said plurality of cutters; and means to actuate simultaneously both of said feeding means.

10. In a machine of the class described, a rotatory shaft, an interiorly open pulley normally loose upon said shaft, a split, expandible ring, housed within said pulley, and disposed to, normally, loosely contact the interior thereof; carried rotatively by said shaft, adjacent said pulley, a carrier; carried, rotatably on its own axis, within said carrier, a spindle having a flattened portion disposed within the split of said ring; and means to rotate said spindle on its own axis, whereby unflattened portions thereof force apart the adjacent ends of said ring and cause it to frictionally clutch the interior of said pulley.

11. In a sheet-feeding, and cutting, machine, a rotatory main shaft; means, operatively connected with said shaft to feed a sheet in one direction; means to sever the sheet, while so fed, into a plurality of 70 smaller sheets of mutually equal width; means to deflect said smaller sheets from each other while so fed; and means, operatively connected with said main shaft, to further feed, simultaneously with each other, 75 a plurality of said smaller sheets, in mutually sequential procession, in a direction angular to said first mentioned direction.

12. In a sheet-feeding machine, a sequence of stationary, consecutive, alike, spaced-apart, stops, having their backs shaped, and disposed to positively engage and their fronts to slidingly contact with, a sheet; another sequence of similar, simultaneously reciprocatable, stops disposed in parallelism 85 with said first-mentioned sequence; means to stationarily support said first-mentioned sequence; and means to reciprocate simultaneously the other sequence, whereby the sheet is, by each, in turn, of said reciprocating stops while advancing, moved slidingly over one of said stationary stops, and, by said stationary stop, held intermittently during retraction of such reciprocating stop. 95

13. In a sheet-feeding machine, a sequence of stationary, consecutive, alike, spaced-apart, stops, having their backs shaped, and disposed to positively engage and their fronts to slidingly contact with, a sheet; another sequence of similar, simultaneously reciprocatable, stops disposed in parallelism with said first-mentioned sequence; means to stationarily support said first-mentioned sequence; means to reciprocate simultaneously the other sequence; and superdisposed means to prevent the sheet from rising unduly upward, whereby the sheet is, by each, in turn, of said reciprocating stops while advancing, moved slidingly over one 105 of said stationary stops, and, by said stationary stop, held intermittently during retraction of such reciprocating stop. 110

14. In a sheet-feeding machine, a pathway, for the sheets, dimensioned and disposed to permit upraising of a sheet therethrough while disposed in a plane transverse the direction of said pathway; laterally yielding members having their tops normally projecting into the path of the sheet in said pathway; means to upraise the sheet into sliding contact with, and above, said members; means to return said members to their normal position after the sheet has cleared them; and means to thereafter lower the sheet to rest upon said tops of said members. 115

15. In a sheet-feeding machine, a plurality of rests disposed to, movably-against-gravity, normally uphold a sheet without 120 125 130

- contacting a portion thereof comprising a part of its edge; disposed normally adjacent one side of said rests, a kicker advanceable, without contacting said rests, in a path 5 alined with and extending beyond such normal location of said part of the edge; disposed at a distance from the opposite side of said rests, means to receive, and support, said sheet in a desired location; means to 10 movably support said kicker out of contact with said rests; and means to impel said kicker through said path with momentum required to drive the sheet off of said rests and to said desired location.
- 15 16. In a sheet-feeding, and cutting, machine, a pathway for the sheets; in said pathway a stationarily supported cutter disposed to sever an initial sheet into smaller sheets; beyond said cutter in said pathway
- 20 20 a stationary divider-member; and means to advance said smaller sheets in the same horizontal plane side-by-side beyond said cutter to, and each side of, said divider-member, whereby the space between said 25 smaller sheets is increased.
- 30 17. In a sheet-feeding, and cutting, machine, a pathway for the sheets; in said pathway a stationarily supported cutter disposed to cut an initial sheet into smaller sheets; beyond said cutter in said pathway a longitudinally extended, therewith parallel, divider-member of angular cross section having its longitudinal angular apex upwardly presented in alinement with the 35 direction of said cut; and means to advance said smaller sheets in the same horizontal plane, side-by-side, beyond said cutter to, and each side of, said divider-member whereby the space between said smaller 40 sheets is increased.
- 45 18. In a sheet-feeding, and cutting, machine, means to feed a sheet in one direction; means to sever the sheet, while so fed, into a plurality of smaller equally wide sheets; means to further feed said smaller sheets in said direction; means to deflect said smaller sheets from each other while so fed; means to further feed simultaneously with each other a plurality of said smaller sheets in a 50 mutually sequential procession, in a direction angular to said first mentioned direction;

and means to sever each in turn of said subdivisional sheets into smaller sheets while being so fed.

19. In a sheet-feeding machine, a pathway, for the sheets, dimensioned and disposed to permit upraising of a sheet there-through while disposed in a plane transverse the direction of said pathway; laterally yielding members having their tops 55 normally projecting into the path of the sheet in said pathway; means, comprising pneumatic-suckers, to upraise the sheet into sliding contact with, and above, said members; means to return said members to their 60 normal position after the sheet has thus cleared them; and means to then break the exhaust in said suckers.

20. In a sheet-feeding machine, a pathway, for the sheets, dimensioned and disposed to permit upraising of a sheet there-through while disposed in a plane transverse the direction of said pathway; yielding, oscilatable, guide-rests pivotally supported on opposite sides of said pathway, having 70 their tops movably held, by aid of gravity, in one plane and normally projecting into the path of the sheet in said pathway; means to upraise the sheet into sliding contact with, and above, said guide-rests, and means 75 to lower the sheet thereon after it has cleared them.

21. In a sheet-feeding machine, means to movably support the sheet without contacting a part of its edge; and means, disposed 85 and actuated to impart to said part of its edge a percussive, following-up, blow whereby the sheet is swept off of said support and caused to take flight in a predetermined direction.

22. In a sheet-feeding machine, means to horizontally movably support a sheet without contacting a portion thereof comprising a part of its edge; and means disposed and actuated to impart to said part of its edge a 95 percussive, following-up, blow whereby the sheet is swept off of said support and caused to take flight in a predetermined direction.

JOHN H. YOUNG.
